UNITED STATES PATENT OFFICE.

ALOIS WILLIAM FRANCIS WEYERS, OF NEW WESTMINSTER, BRITISH COLUMBIA,
CANADA.

DOUBLE-STAIR-GRAVE CONTINUOUS KILN.

1,102,970.

Specification of Letters Patent.

Patented July 7, 1914.

Application filed April 10, 1913. Serial No. 760,176.

To all whom it may concern:

Be it known that I, ALOIS WILLIAM FRANCIS WEYERS, of the city of New Westminster, in the Province of British Columbia, Canada, have invented certain new and useful Improvements in Double-Stair-Grate Continuous Kilns, of which the following is a specification.

My invention relates to improvements in double stair grate continuous kilns, and the object of my invention is to devise a kiln in which all kinds of high and low grade clay products can be burned, and which shall burn these products evenly throughout from top to bottom, and thus produce a more uniform and higher class product than has hitherto been obtainable in ordinary kilns and with a greatly decreased consumption of fuel.

I attain this object by the construction illustrated in the accompanying drawings in which:

Figure 1, is a transverse sectional elevation of the kiln apartments, on the line W—W in Fig. 3. Fig. 2, is a part longitudinal sectional elevation on the line X—X in Fig. 1. Fig. 3, is a sectional plan on the line V—V in Fig. 1, showing four apartments of the kiln, side, and main flue. Fig. 4, is a view of the top step of the stair grate. Fig. 5, is a view of one of the lower steps of the stair grates, showing the part cut away in the raised edge. Fig. 6, is a perspective view of the grates showing the method of supporting the steps. Fig. 7, is a plan detail of a pair of steps and their support.

Similar letters refer to similar parts throughout the several views.

The nature of my invention is as follows:—It consists of a continuous kiln with apartments having a cross section similar to that shown in Fig. 1, in which A is the space for receiving and burning the products, B the side walls, and C is the arch of the roof. The upper part of the roof is constructed as shown, with longitudinal recesses D, which are filled in with sand. The several apartments A of the kiln are each complete in themselves, and are connected with each other by the openings E in the side walls B, and the side flues O, making the kiln a continuous one, and thus utilizing the heat produced in the apartments to the very extreme. The back end of each apartment is closed by a wall Q in Fig. 3, be-

tween which walls the main flue Y runs at any convenient height while the front end of the apartments has a door I through which access may be had to their interiors, as shown in Fig. 3.

The grates are constructed in upper and lower tiers, the upper being arranged in staggered relation with respect to the lower, as clearly shown in Figs. 1 and 2 of the drawings, each apartment containing an upper and lower grate. The upper grate F, and the lower grate G, are built in the form of stairs, in which H represents the steps of the upper grate F, and J represents the steps of the lower grate G. These steps, H and J, are removable, and rest, in the upper grate, on the outer face of the grate and the side wall B, and in the lower grate, on the outer face of the lower grate and the outer face of the upper grate. The inner ends of the steps are as shown in Fig. 4 and Fig. 5, and rest in notches F² in the upper grate, and G² in the lower grate formed in the aforesaid faces and side walls, as shown in Fig. 6, while the outer ends of the steps are made with a raised edge, and cut away as shown in Fig. 5. These outer ends also rest on the faces F' and G' of the grates in a similar manner to the inner ends, and are cut away as shown to allow of their engaging behind the outer faces of the grates to keep the steps in place. The raised edges are formed for the purpose of preventing the fuel from spilling over as it is fed on to the steps. The uppermost step of all in each grate is made with its outer raised edge continuous, as shown in Fig. 4. The grates F and G are made of fireclay, and their steps H and J may be made perforated, as shown in Figs. 4 and 5, or solid, according to the size and quality of the coal it is desired to use in the working of the kiln. The upper grates F and the lower grates G may be used entirely independent of each other, since, if it is only required to use the upper set of grates, the fire would only be maintained thereon, and vice versa, if it were only necessary to use the lower set of grates, the fire would only be kept on them, while if both sets of grates were to be used together, the fires would be maintained on both of them. The separate openings K and L, for the fuel supply, makes the grates independent of each other, since the openings K only feed the upper grates, and the open-

ings L the lower grates. For different kinds of clay products the fire bridges can be arranged open or closed between the grates. For example, for burning hollow-
ware, such as drain and sewer pipes and the like, it is preferable to direct the flame upward, in which case the fire bridges would be closed. This is done by building a wall of fire brick between the outer faces of the grates, as shown, F³ and G³, in Fig. 6. This wall is of equal thickness to the outer face and incloses the fire, so that the flame, instead of spreading outwardly, will be directed upward. Small holes, F⁴ in Fig. 6,
15 are left in the walls F³, G³, thus built, in the way of the inclined bridges M, to allow of the fuel being fed to the lower grates.

To provide for feeding the coal on to the grates, the openings K and L are constructed 20 in the roof, running from the upper side of the roof to the inside of the arch C, each opening being situated directly in line with the center line of the grates. The coal passing through the openings L, to supply the 25 on to the upper step of the grates F and from there it spreads down and on to the lower steps of these grates, while that passing through the openings L, to supply the grates G, falls on to the inclined steps M, 30 and from there to the upper steps of the grates G, and from there to the lower steps. Through the openings E in the side walls B the necessary air for combustion passes, 35 from one apartment to another, while a continuous circulation of heat through the entire kiln is provided for by the side flues O, which connect one row of apartments with the other. The flue gases pass through the opening N in the roof of the apartments, 40 and escape into the main flue Y, which runs between the rows of apartments, as shown in Fig. 3. The openings N are connected with this main flue by suitable pipes, which can be removed at will.

45 P is a metal reservoir for holding water, with pipe connections R running from it to the openings E by way of the holes S in the side walls B. This reservoir P is placed, full of water, in one of the openings N, 50 after the eduction pipe therefrom has been removed, in the apartment last burned and adjacent to the apartment which is to be burned. The cocks in the pipe connections are opened when burning is taking place, 55 and the water then passes from the reservoir P, which is always kept full, to the openings E and through them to the space T underneath the grates F. In this space the water becomes steam, and coming in contact with 60 the fuel gases and combustion air, circulates through and over the grates F and G, thus preventing the coal from forming clinker on the grates. The openings U are provided to allow the steam to pass from the space 65 T to underneath the grates G. It will be

seen, therefore, that a perfect control of the temperature of the kiln can be had, which control is necessary to secure a perfectly burned and uniform product. By the use of the double stair grate this uniformity of temperature can be regulated as required, as the lower grates provide that it is not necessary to burn faster and more severe on the upper grates than is wanted in order to burn the upper part of the kiln 70 sufficiently, and further, the fuel consumption is reduced to a minimum, as the heat produced from the coal is utilized to the utmost. It will be seen, therefore, that I have devised a double stair grate continuous 75 kiln, in which a uniform temperature can be obtained and maintained, capable of burning all kinds of high or low grade clay products, and of producing a more uniform and higher class product than has hitherto 80 been obtainable at the same cost. It will also be seen that the fuel consumption will be reduced to the minimum, since, as the temperature is always under control, no more fuel need be used than is absolutely 85 necessary, and the heat obtained from this fuel is applied and utilized to the utmost advantage. A further advantage is, that the steps of the grates being removable, 90 they can be taken out and changed very 95 quickly, if necessary, this is also a great convenience for cleaning the grates. The double stair grate can be fixed to any previously built continuous kiln of any type.

It will, of course, be understood that to 100 open and close the fire bridges or the space between the several grates all that is done is when the space is to be closed for the purpose of sending flames up, to merely take some fire brick and close the space by a 105 wall. The fire bridges may then be termed closed while they would be open when there is no wall built.

What I claim as my invention is:

1. In a continuous kiln, a number of independent adjoining apartments with intervening walls between them, passages in said walls to connect adjoining apartments with each other, openings in the roofs of said apartments for escape of fuel gases, 110 pipes connecting said openings to a main flue, two sets of stair grates in staggered relation in each of said apartments and means for supplying fuel to said grates, all substantially as set forth.

2. In a continuous kiln, a number of independent adjoining apartments with intervening walls between them, side flues connecting a series of said adjoining apartments with another series of adjoining apartments, 115 a series of upper stair grates contained within each said independent adjoining apartments, a series of lower stair grates contained within each said independent adjoining apartment, said lower stair grates 125

120

125

130

being adjacent to said upper stair grates, but separable therefrom and set in staggered relation thereto, feed openings for supplying fuel to said upper and lower stair grates, 5 all substantially as set forth.

3. In a continuous kiln, independent adjoining apartments with intervening walls between them, upper and lower stair grates in staggered relation in each of said apartments, steps for said grates adapted to be detachably supported in step-receiving notches formed in the supporting walls of said grates, and means for supplying fuel to said steps, as and for the purpose specified.

10 4. In a continuous kiln, independent adjoining apartments with intervening walls between them, upper and lower stair grates in staggered relation in each of said apartments, steps for said grates adapted to be detachably supported in step-receiving notches formed in the supporting walls of said grates, means for preventing longitudi-

nal displacement of said steps, and means for supplying fuel to said steps, as and for 25 the purpose specified.

5. In a continuous kiln, independent adjoining apartments with intervening walls between them, upper and lower stair grates in staggered relation in each of said apartments, said grates having step-receiving notches formed in their supporting walls, steps for said grates adapted to be slidably engaged into the said notches, the said steps having their outer ends upwardly turned whereby the fuel may be prevented from spilling over the ends of the said steps, and means for supplying fuel to said steps, as and for the purpose specified.

Dated at Vancouver, B. C. this 29th day 40 of January, 1913.

ALOIS WILLIAM FRANCIS WEYERS.
